UNITED STATES PATENT OFFICE

2,532,578

MATERIAL BREAKING SHELL

Russell Spencer, Sullivan, Ind., assignor to Cardex Corporation, Chicago, Ill., a corporation of Illinois

Application August 15, 1946, Serial No. 690,767

9 Claims. (Cl. 102—25)

1

This invention relates to a material breaking shell and more particularly to a device of this character which employs highly compressed gas, such as air, as the material breaking medium.

In a shell of this type an enclosed chamber is charged with gas under high pressure and this charge is released through a valve controlled discharge orifice. It is essential that this valve fit tightly upon its seat when the chamber is being charged so that no leakage will occur and so that the chamber may be more quickly brought up to its full working pressure. However, the valve may start to leak because of foreign matter that is deposited upon its seating surfaces and, for the further reason that the valve tends to seat in the same position each time it is closed and, therefore, will not maintain its seating surfaces ground to a close fit.

In accordance with the invention, means are provided for causing the valve to rotate each time it moves into its closed position. This rotational movement of the valve not only serves to remove any foreign matter that may be deposited on its seating surfaces, but, in addition, causes the valve to seat in a different position each time it is closed.

A preferred embodiment of the invention is illustrated in the drawings in which:

Figure 1 is a longitudinal sectional view through the material breaking shell.

Figure 2 is a side elevational view of the valve operating piston, and

Figure 3 is an end view of the piston of Figure 2.

The shell includes a container which is made up of a central hollow body 5, a discharge cap 6 threaded into one end thereof and a control cap 7 threaded into the other end thereof. The shank 6' of the discharge cap is shaped at its inlet end to form the seat 8 for a valve head 9. Through the side wall of the discharge cap 6 are formed a plurality of ports 10 for the discharge of the compressed gas. These ports 10 are preferably rearwardly inclined so that the discharging gas tends to urge the shell deeper into the drill hole into which the shell is located. The forward end of the cap 6 is formed with an opening 11 through which the valve stem 12 projects to serve as a guide for the valve.

A supply conduit 14 is threaded into the end of the control cap 7 and this conduit delivers highly compressed gas into the inner cylinder portion 15 of this cap. Operating within the cylinder 15 is a piston 16, having a piston rod 17 threaded into the valve head 9. When gas under pressure is delivered through conduit 14, it acts

2

upon the head of piston 16 and forces it in a right-hand direction, as viewed in Fig. 1, to force the valve head 9 upon its seat 8.

It is intended that the piston 16 be so fitted within its cylinder 15 that the incoming gas can flow therewith and into the chamber within the central body 5. Secured to the inner face of the piston 16, by means of a nut 18 is a cup leather 19. The gas which flows past the piston 16 also flows past this cup leather 19 so that the gas can pass into the charge receiving chamber of the body 5.

Between the central body 5 and the control cap 7 is clamped a disc 21 and it is preferable that a sealing gasket 22 be disposed on at least one side of this disc 21. A hat leather 23 is secured to disc 21 by means of an annular ring 24 and bolts 25. The hat leather 23 fits tightly upon the outer surface of the piston rod 17 to seal 20 against gas leakage.

Between the cup leather 19 and the hat leather 23 is formed a chamber 27. It will be noted that the cup leather 19 and the hat leather 23 are so disposed that the pressure within the chamber 27 will tend to force these leathers into tight engagement with the cylinder 15 and piston rod 17 respectively, to prevent leakage of gas from this chamber 27 past these leathers during any stage in the operation of the cartridge.

30 A communication, however, should be provided between the chamber 27 and the charge receiving chamber of the body 5, and, as here shown, this is accomplished by forming a passageway 28 through the piston rod 17. A port 29 from the passageway 28 opens into the chamber 27 and a port 30 opens from the passageway 28 into the chamber of body 5.

As an important feature of the invention means are provided to cause the piston to rotate as it is being urged in the direction to position the valve head 9 upon its seat 8. This means involves the provision of surfaces against which the charging gas will impinge to thereby cause the piston to rotate. These surfaces 45 are, therefore, spirally arranged with respect to the axis of the piston so that the charging gas in flowing past the piston 16 will develop a reactive force which will rotate the piston and thereby the valve head 9.

As here shown, these spiral surfaces against which the charging gas impinges, are formed by flutes 31 which extend the full length of the periphery of the piston 16. These flutes 31 may be of any cross-sectional formation which may be conveniently constructed and they should in-

cline preferably on the order of about 30° with respect to the piston axis. It will be appreciated that the flutes 31 provide the aforementioned fit between the piston 16 and its cylinder 15 that allows the gas to flow past the piston 16.

When the shell is being charged by means of the conduit 14 and the gas flows past the piston 16, the movement of the gas through the flutes 31 causes the piston 16 to rotate. The gas continues past the cup leather 19 into the chamber 27 and through the passageway 28 and its ports 29 and 30 into the chamber within body 5. The valve 9 will fit tightly upon its seat 8, due to the gas pressure developed in cylinder 15, and prevent escape of this charge of gas because the rotational movement of the valve head 9 will clean the seating surfaces. After the chamber within body 5 has been fully charged, the supply of gas to conduit 14 is cut off and this conduit 14 is vented to exhaust the gas from the cylinder 15. This will remove the gas pressure from piston 16 and, as a high pressure still exists in chamber 27, the piston will be moved in a left-hand direction to unseat the valve head 9. The valve head 9 will remain unseated until the gas has been completely discharged from body 5 because gas will remain under pressure within the chamber 27 for an appreciable length of time since it can escape only through the restricted passageway 28.

It has been pointed out above that the cup leather 19 prevents the escape of gas from the chamber 27 past the piston 16. Consequently, no gas from the chamber 27 will be permitted to flow through the flutes 31. It will be appreciated, therefore, that the cup leather 19 functions to prevent rotation of the piston 16 when the valve head 9 moves away from its seat 8.

When the gas within the hollow body 5 drops to atmospheric pressure, the chamber 27 will be vented through the passageway 28 so that chamber 27 will reach atmospheric pressure. When the next charge of gas is supplied through conduit 14, movement of the piston 16 in a right-hand direction will not be resisted inasmuch as no pressure then will exist in chamber 27.

Having thus described the invention, I claim:

1. A material breaking shell comprising a container having a chamber to receive a high pressure gaseous charge and having a discharge orifice therefrom, a valve means for closing said orifice, a valve operating means having a connection to said valve means to control its position, said container having an inlet for connection to a source of charging gas, said valve operating means including means acted upon by the flow of charging gas into said chamber from said inlet for causing rotation of the valve means as it moves toward said orifice, and means to prevent rotation of said valve means as it moves away from said orifice.

2. A material breaking shell comprising a container having a chamber to receive a high pressure gaseous charge and having a discharge orifice therefrom, a valve means for closing said orifice, a valve operating means having a connection to said valve means to control its position, said container having an inlet for connection to a source of charging gas, said inlet being on the opposite side of said valve operating means from said chamber so that the charging gas flows past said valve operating means into said chamber, said valve operating means including means in the path of the flow of charg-

ing gas into said chamber to be acted upon by the charging flow of gas and thereby cause rotation of the valve means as it moves toward said orifice, and means to prevent rotation of said valve means as it moves away from said orifice.

3. A material breaking shell comprising a container having a chamber to receive a high pressure gaseous charge and having a discharge orifice therefrom, a valve means for closing said orifice, a valve operating means having a connection to said valve means to control its position, said valve operating means including means in the path of the flow of charging gas into said chamber for causing rotation of the valve means as it moves toward said orifice, and means to prevent rotation of said valve means as it moves away from said orifice.

4. A material breaking shell comprising a container having a chamber to receive a high pressure gaseous charge and having a discharge orifice adjacent one end thereof and inlet means adjacent the other end, a valve means for closing said orifice, a valve operating means disposed between said inlet means and said chamber and past which the incoming gas must flow to charge the chamber, said valve operating means including surfaces inclined to its axis and against which the charging gas impinges to cause rotation of the valve operating means, said valve operating means being connected to and serving to rotate said valve means as it moves toward said orifice, and means to prevent rotation of said valve means as it moves away from said orifice.

5. A material breaking shell comprising a container having a chamber to receive a high pressure charge and having a discharge orifice adjacent one end of the container, said container having an inlet at its opposite end, a valve means for closing said orifice, a piston connected to said valve means to urge it toward said orifice, said piston being located between said inlet and said chamber so that the incoming gas flows past the piston in charging the chamber, said piston including means to be acted upon by the incoming gas for rotating the piston and thereby rotating the valve means as it moves toward said seat, and means to prevent rotation of said valve means as it moves away from said orifice.

6. A material breaking shell comprising a container having a chamber to receive a high pressure charge and having a discharge orifice adjacent one end of the container, said container having an inlet at its opposite end, a valve means for closing said orifice, a piston connected to said valve means to urge it toward said orifice, said piston being located between said inlet and said chamber so that the incoming gas flows past the piston in charging the chamber, said piston having longitudinal flutes along its surface and at an angle to its axis, the flow of gas through said flutes in charging said chamber, serving to rotate said piston and to thereby rotate said valve means as it moves toward said orifice, and means to prevent rotation of said valve means as it moves away from said orifice.

7. A material breaking shell comprising a container having a chamber to receive a high pressure fluid charge and having a cylinder, said container having a discharge orifice and an inlet into said cylinder, a valve means for closing said orifice, a piston in said cylinder between said inlet and said chamber to operate

said valve means, said piston having fluid conducting passageways to pass fluid from said inlet side to the other side, said passageways being disposed at an angle to the axis of the piston to cause rotation of the piston and thereby rotate the valve means, and means to prevent rotation of said valve means as it moves away from said orifice.

8. A material breaking shell comprising a container having a chamber to receive a high pressure gaseous charge and having an internal cylinder, a partition between said chamber and cylinder, said chamber having a discharge orifice therefrom, a valve means for closing said orifice, a piston operable in said cylinder and having a connection extending through said partition to said valve means to actuate the valve means, said chamber having a restricted communication with said cylinder, said cylinder having an inlet to deliver gas under pressure on the side of the piston to thereby urge the valve means to closed position, said piston having passageways lengthwise therealong presenting angularly disposed surfaces against which the delivered gas impinges to thereby rotate the piston and the valve means, the gas, after flowing through said passageways, flowing through said restricted communication and into said chamber, and means to prevent rotation of said valve means as it moves away from said orifice.

9. A material breaking shell comprising a container having a chamber to receive a high pressure gaseous charge and having an internal cylinder, a partition between said chamber and cylinder, said chamber having a discharge ori-
